BRAIDING MACHINE

Richard Marogg, Hastings on Hudson, N. Y.

Application November 21, 1950, Serial No. 196,869

15 Claims. (Cl. 87—46)

1

My invention relates to machines for braiding together strands of metal or other material.

One of the objects of my invention is to provide a braiding machine in which the rotating parts are substantially balanced at all times as distinguished from those machines in which parts, sometimes of substantial weight, move towards and away from the axis of rotation. Another object is to provide a machine which may be operated at comparatively high speed without vibration and noise. Another object is to provide a machine in which friction losses are very low and which may, therefore, be operated by means of a comparatively small motor. Another object is to provide a machine in which the tension on the strands which are being braided together is maintained substantially constant at all times so that a uniformly braided product is produced and it is possible to braid extremely tenuous strands without danger of breaking. Another object is to provide a braiding machine on which the strands may be carried on comparatively large diameter spools so that stoppages of the machine in order to replenish the strand supply are very substantially reduced. Another object is to provide a braiding machine which can be adapted to braid at any angle and with or without a core, so that either tubes may be braided or a sheathing may be braided in place. A further object is to provide a braiding machine in which there is never any slack in the strands as is the case with the Maypole type of machine.

I accomplish these objects by means of the novel elements and the combinations and arrangements thereof described below and illustrated in the accompanying drawing in which—

Fig. 1 is a fragmentary plan view of my machine;

Fig. 2 is a fragmentary vertical section through the machine with certain portions broken away and certain portions omitted for clarity;

Fig. 3 is a fragmentary plan view with portions omitted showing a modification;

Fig. 4 is a fragmentary elevation view of the modified device shown in Fig. 3;

Fig. 5 is a fragmentary plan view similar to Fig. 3 showing another modification;

Fig. 6 is a fragmentary elevation view of the modification shown in plan in Fig. 5;

Fig. 7 is an enlarged section taken in the plane 1—1 of Fig. 5;

Fig. 8 is an enlarged plan view of a detail, partially in section;

Fig. 9 is a fragmentary front elevation view of the detail shown in Fig. 8;

2

Fig. 10 is an enlarged side elevation view of a spool with a holder therefor and illustrating the mechanism which maintains the tension uniform on the strands running from the spools;

Fig. 11 is a right hand side view of the device shown in Fig. 10 with portions broken away and portions in section showing the construction thereof;

Fig. 12 is a top plan view of a spool and the tension mechanism drawn to an enlarged scale;

Fig. 13 is a top plan view of one of the bases on which the spools on the inner carrier are mounted as seen through the plane 13—13 in Fig. 14;

Fig. 14 is a left hand side view of the device shown in Fig. 13;

Fig. 15 is a right hand side view of the device shown in Fig. 13;

Fig. 16 is a front elevation view of the device shown in Fig. 13;

Fig. 17 is a view similar to Fig. 14 showing the inner gates open;

Fig. 18 is a view similar to Fig. 15 showing the outer gates open;

Fig. 19 is a top plan view similar to Fig. 13 showing a modified type of gate;

Fig. 20 is a left hand side view of the device shown in Fig. 19 and is similar to Fig. 14;

Fig. 21 is a right hand side view of the device shown in Fig. 19 and is similar to Fig. 15;

Fig. 22 is a section of Fig. 20 in the plane 22—22 with portions broken away to show details of construction;

Fig. 23 is a front elevation view similar to Fig. 20 but showing the inner gates open;

Fig. 24 is a section of Fig. 22 in the plane 24—24 showing the inner gates closed and the outer gates open;

Fig. 25 is a diagrammatic illustration of the cam tracks which have been projected radially outwardly from Fig. 1, and which illustrates the approximate relative positions of the high and low portions thereof in order to effect a proper timing of the movements of various elements;

Fig. 26 is a fragmentary plan view, similar to Fig. 1, of a further modification of my machine;

Fig. 27 is a fragmentary vertical section, similar to Fig. 2, of the machine shown in Fig. 26;

Fig. 28 is a plan view of one of the spools shown in Fig. 26 but drawn to an enlarged scale and projected on a plane above the spool and parallel to the axis thereof;

Fig. 29 is a front view, partially in section and partially in elevation, of the parts shown in Fig. 28;

Fig. 30 is a fragmentary transverse section of

the spool shown in Figs. 28 and 29, drawn to an enlarged scale and showing the tension regulating means;

Fig. 31 is a fragmentary enlarged section of a detail of the tension regulating means; and

Fig. 32 is a fragmentary section of Fig. 29 in the plane 32—32.

Referring to the drawings and first to Fig. 2, my device comprises a hollow, vertically-disposed, stationary shaft 1 which is surrounded by an inner tubular shaft 2 and an outer tubular shaft 3. Secured to the inner shaft 2 near the bottom thereof is a driven gear 4 and secured to the outer tubular shaft 3 near the bottom thereof is a driven gear 5. The gears 4 and 5 are in mesh with the driving pinion 6 mounted on shaft 6' to which is secured the gear 7. The gear 7 is driven by the pinion 7' on the shaft 8 which is driven from a source of power (not shown). Keyed to the outer, tubular shaft 3 and mounted on the ball bearings 9 is a circular table or spool carrier 10 which rotates counter-clockwise. Keyed to the inner, tubular shaft 2 is another circular table or spool carrier 11 which is driven in a clockwise direction; it being apparent that the gears 4 and 5 are rotated in opposite directions by means of the pinion 6. Fixedly secured to the stationary shaft 1 at the top thereof is a third table 12 which carries a cam track 13 which will be described below.

Referring now to both Fig. 1 and Fig. 2, there are mounted on the carrier 11, which will be referred to hereafter as the inner carrier, a plurality of equi-circumferentially spaced, strand-carrying spools 14, as shown in Fig. 1. As illustrated, the inner carrier is provided with twelve spools but, within practical limits, any even number of spools may be employed. Mounted on depending legs 15 (see Fig. 2) which are secured to the bottom of the outer carrier 10 is an equal number of equi-circumferentially spaced, strand-carrying spools 16. The strands 17 which run from the spools 14 extend directly to the braiding zone 18. The strands 19 running from the spools 16 extend upwardly through openings 20 in the outer carrier 10 and over pulleys 21 which are secured by means of brackets 22 on the bearing supports 23 secured to the top of the outer carrier 10 around the outer edge thereof. By referring particularly to Figs. 8 and 9, it will be noted that the bearings on the top of the bearing supports 23 comprise an outer housing 24 in which the spindle 25 is secured by means of the snap ring 26 so that it may oscillate. Secured to the spindle 25 and extending therethrough coaxially therewith, is a tube 27. The strands 19 run from the pulleys 21 into and through the tubes 27 and thence to the braiding zone 18.

In order to braid the strands 17, which run from the spools on the inner carrier, with the strands 19 which run from the spools on the outer carrier, it is necessary to provide some means whereby the strands 19 may alternately pass over and under the strands 17. This involves first, some means whereby the strands 19 are elevated to a height so that they may pass over the spools 14, and thereafter lowered to a position where they may pass beneath the spools 14, all in properly timed relation to the relative rotative movements of the carriers; and, second, some means whereby passageways are provided for the strands 19 through the supports which carry the spools 14. The first mentioned means involves mechanism for oscillating the tubes 27 from the position shown in solid lines in Fig. 2

to the position shown in dotted outlines in this figure. In other words some mechanism must be provided for oscillating the tubes 27 about the axes of the spindles 25 and, in passing it may be pointed out that, in order to prevent the strands from becoming slack during the oscillating movements of the tubes 27, the axes of the spindles 25 cannot intersect the axis 28 about which the carriers rotate because the braiding point or zone is laterally offset from the axis 28, as is best shown in Fig. 8. In other words, the axes 29 of the spindles 25 should be approximately tangent to a vertical cylinder, such as shown in dotted outline at 18 in Fig. 8, which defines the braiding zone.

One means of oscillating the tubes 27 about the axes of the spindles 25 is illustrated in Figs. 3 and 4. Here, a rocker arm 30 which actuates two adjacent tubes is pivotally mounted to oscillate up and down on the axis of a boss 31 secured to the outer carrier 10. The extremities of the arm 30 are connected to the adjacent tubes 27 by links 32 having ball joints 33 at the extremities thereof which connect the links, respectively, to the tubes 27 and the arm 30. A cam follower 34 is pivotally mounted at one end of the arm 30 and rides in a slot 35 in the cylindrical cam plate 36. Thus, when one of the tubes 27 is in its highest position so that the strand 19 running therefrom may pass over one of the spools 14, the strand 19 running from the other tube 27 is in its lowest position so that it may pass under an adjacent spool 14.

In Fig. 2, I have shown a slightly different mechanism for oscillating the tubes 27 in that each tube is connected to a crank 37 by a link 38 and ball and socket joints 39. A cam follower 40 mounted on the end of the crank 37 runs in a cam slot 41 in the cylindrical cam plate 42 and oscillates the crank 37 about the bearing 43 between the position shown in solid outline in Fig. 2 and the position shown in dotted outline in Fig. 2. Thus, the tube 27 and the strand 19 are moved from the positions shown in solid outlines in Fig. 2 to the positions shown in dotted outlines.

In Figs. 5, 6 and 7, I have shown a further modification of the means for oscillating the tubes 27 which includes a means for relieving the tubes 27 of bending stress due to tension on the strands 19. Thus, a rod 44 is welded or otherwise secured to each of the tubes 27 at the free end thereof and extends outwardly therefrom with its axis approximately tangent to the cylindrical braiding zone. Mounted on each of the rods 44 is a conical roller thrust bearing 45 which is adapted to run on the lower side of a track 46. Adjacent the conical or thrust bearing 45 there is mounted on the rod 44, a cylindrical roller bearing 47 which is adapted to run on the top or upper side of a track 48. By reference to Fig. 7, it will be apparent that the cooperation of the bearing 47 with the track 48 will prevent a downward movement of the associated tube 27 while the cooperation of the thrust bearing 45 with the track 46 will prevent upward and also inward movement of the tubes 27. The tracks 46 and 48 are secured together at spaced intervals by means of the tie plates 49 and together form a cam slot 50 which controls the oscillating movements of the tubes 27.

Referring now particularly to Figs. 19, 20, 21, 22, 23 and 24, in connection with Figs. 2, 10 and 11, it will be apparent from Figs. 2, 10 and 11, that each of the spools 14 is supported on a base

plate 51 which is provided at each side of the bottom thereof with a depending rectangular bar 52 which may be bolted, welded or otherwise secured thereto. The bars 52, on the outer sides thereof, are provided with a pair of spaced lugs 53, and on the inside thereof with a pair of spaced lugs 54. The lugs 53 cooperate with gates 55 and the lugs 54 cooperate with gates 56 to support the bases 51 of the spool supports. The gates 55 are mounted in bearings 57 in the side bars 58, which are bolted or otherwise secured by means (not shown) to the table or carrier 11, as shown in Fig. 2, and the gates 56 are also mounted in bearings 59 in the side bars 58. The shafts 60 and 61 on which outside gates 53 are mounted project outwardly beyond one of the bars 58, as best shown in Figs. 19 and 22, while the shafts 62 and 63 on which the inner gates are mounted project outwardly beyond the opposite side bar 58. Secured to the projecting end of the shaft 61 is an arm 64 and mounted on the projecting end of the shaft 60 is an arm 65. Adjacent its free end, the arm 65 is provided with a rectangular slot 66. Secured to the free end of the arm 64 is a pin 67 which extends through a block 68 which is adapted to slide in the slot 66 and which has a running fit on the pin 67. The pin 67 projects somewhat beyond the arm 65 and has a ball or roller bearing 69 mounted thereon which is adapted to run in a cam slot which will be later described. When the arms 64 and 65 are in the positions shown in Figs. 20 and 23, the outer gates 55 are closed and thus form supports for the bases 51 on which the inner spool carriers are mounted. By moving the bearing 69 upwardly the gates 55 may be opened.

Secured to the projecting portion of the shaft 62 (see Figs. 19-22) is an arm 70, and secured to the projecting end of the shaft 63 is an arm 71 which carries at its free end a pin 72, similar to the pin 67, which extends through the block 73 adapted to ride in the slot 74 in arm 70, and is provided at its free end with a ball or roller bearing 75, similar to the bearing 69, which is adapted to run in a cam slot, which will be later described, to open and close the inner gates. Thus, when the arms 70 and 71 are in the positions shown in Figs. 21 and 24, the inner gates 56 are closed and also form supports for the bases 51 of the inner spool carriers. However, it will be apparent that by moving the bearing 75 downwardly from the position shown in Fig. 21, the inner gates may be opened.

By reference to Fig. 2, it will be apparent that the axes of the shafts 60, 64, 62 and 63 are inclined to the axis of rotation 28 at substantially the same angle as the strands 19 when in their lowermost positions, and that the axes of the pins 67 and 72 on which the bearings 69 and 75, respectively, are mounted, are parallel to these shafts. Therefore, the cam tracks or slots which guide the bearings 69 and 75 must have cam guiding surfaces which are generated by lines which move parallel to the axes of the bearings 69 and 75.

Secured to brackets 76 (see Fig. 2) which are mounted on the carrier 10, is a plate 77 (see also Fig. 1) the opposite sides of which are inverted frusto-conical surfaces, and which said plate is provided with a slot 78 in which the roller 69 rides. This slot is represented diagrammatically in Fig. 25 by the line 78 and, of course, should be slightly wider than the diameter of the roller 69 so that, at any instant, the roller touches only

the top or bottom surface of the slot and not both.

Mounted on the stationary table 12 is a second inverted frusto-conical plate 13 having a slot 19 therein (see Fig. 2) in which the roller 75 rides. This slot is diagrammatically represented by the line 19 in Fig. 25, and is slightly wider than the diameter of the roller 75.

As illustrated in Fig. 2, it will be noted that the strand 19 is about in its lowermost position and the outer gates 55 are open. Bearing in mind that the axis of the roller 69 and also the axis of the roller 75 are each located approximately in a vertical, radial plane passing through the center of the spools 14, or their supports, it will be apparent that, since the outer gates must be opened to pass the strands 19, the inner gates must be closed in order to support the spools. Hence, all the rollers 69 must be at the high points of their travel and all the rollers 75 must also be at the high points of their travel in order to maintain, respectively, the outer gates open and the inner gates closed. As soon as the strands pass the outer gates, the outer gates must close and the inner gates must open; and, as soon as the strands clear the inner gates, the outer gates must again open. By reference to Fig. 25, and bearing in mind that the carrier for the spools 14 is rotating in a clockwise direction, the relative angular disposition of the high and low spots in the cam tracks 78 and 79 must be approximately as shown in Fig. 25.

Instead of having the gates vertical when in the closed position, as shown in Figs. 19-24, the machine may be speeded up to an appreciable degree by using the preferred type of gates shown in Figs. 13-18 because less movements of the gates are required in order to pass the strands 19. Since the spool supports, as shown in Figs. 13 to 18, inclusive, may be identical with the supports shown in Figs. 19 to 24, inclusive, except for the specific shape of the gates and the shape of the bars depending from the base plates 51 of the supports for spools 14, the same numbers 40 will be used in the following description as were used above where the parts are identical. Thus, on each side of the base plates 51 of the spool supports are depending, inverted, V-shaped bars 80 which are analogous to the bars 52 shown in Figs. 19-24, inclusive. At their outer edges, the bars 80 are provided with spaced, downwardly-inclined lugs 81 which cooperate with the outer gates 82, and at their inner edges with spaced, downwardly-inclined lugs 83 which cooperate with the inner gates 84. The gates 82 are mounted on shafts 60 and 61 which have bearings 57 in the bars 58, which may be identical with the bars 58 described above, and which are bolted or otherwise secured by means (not shown) to the table or carrier 11, as shown in Fig. 2. The inner gates 84 are mounted on shafts 62 and 63 which also have bearings 59 in the side bars 58. The shafts 60 and 61 project beyond one side of the side bars 58 as best shown in Fig. 13. Mounted on the projecting portion of the shaft 61 is an arm 64, and mounted on the shaft 60 is an arm 65 having, adjacent its free end, a slot 66. A pin 67 which is secured to the arm 64 adjacent the free end thereof passes through the slot 66 in arm 65, and is provided at the free end thereof with a ball or roller bearing forming a cam follower 69 which is adapted to ride in the slot 78 in cam plate 77 in precisely the same way as the cam follower 69 illustrated in Figs. 19-23, inclusive. The shafts 62 and 63 on which the

inner gates 84 are mounted project through the other side bar 58, as best shown in Fig. 13. Mounted on the projecting portion of the shaft 62 is an arm 70 and mounted on the projecting portion of the shaft 63 is an arm 71 carrying at its free end a pin 72 which passes through a slot 74 in the arm 70 and which carries at its free end a cam follower 75, in the form of a ball or roller bearing, which is adapted to ride in the slot in cam plate 13.

It will be apparent from Figs. 14 and 18, that when the arms 64 and 65 are in their lowermost position, as shown in Fig. 14, the outer gates 82 will be closed and form supports for the base 51 of the spool carriers and, when the arms 64 and 65 are moved into their uppermost position, the gates 82 will be opened, as shown in Fig. 18. Similarly when the arms 70 and 71 are in their uppermost position, as shown in Figs. 15 and 18, the inner gates 84 will be closed and also form supports for the bases 51 of the spool carriers. When the arms 70 and 71 are in their lowermost position, the inner gates 84 will be open, as shown in Fig. 17. Thus, when the cam follower 69 is down, the outer gates will be closed but when the cam follower 75 is down, the inner gates will be open; and, when the cam follower 69 is up, the outer gates will be open but, when the cam follower 75 is up, the inner gates will be closed.

From the foregoing it will be apparent that, in order to support the spool carriers on the inner table either the gates 82 or 84 must be closed, but either set of gates may be open while the other set is closed. In order to pass a strand 19 beneath the spools 14 the outer gates must be open until the strand passes therethrough, whereupon the outer gates must close and the inner gates open until the strand passes through the inner gates, whereupon the inner gates must close and the outer gates must again open to pass the strands out so that they may move upwardly and over the spools 14.

In order to effect a uniform braiding, a uniform tension must be maintained at all times both on the strands 17 and 19. Since the braiding progresses at a uniform rate and the strands are withdrawn from the spools 14 and 16 at a uniform rate, it will be apparent that, as the quantity of the strands on the spools diminishes, the spools must rotate at a gradually increasing rate of speed. It will also be apparent that the turning moment exerted on a spool by the uniform tension on the strand will be greatest when the spool is substantially filled and least when the spool is substantially empty because the strand, as it is drawn off the spool, is tangent to the strand body on the spool and the distance between the axis of the spool, measured in a direction normal to the strand, decreases as the quantity of strand material on the spool decreases. For this reason a uniform braking pressure cannot be maintained on the spools and, at the same time, maintain a uniform tension on the strands. I have therefore provided a controlled braking means for each spool in which the braking effect gradually diminishes as the supply of strand material on the spool diminishes.

Referring now particularly to Fig. 2 for the assembly and Figs. 10, 11 and 12 for the details, the spools 14 and 16 are mounted on spindles 85 which in turn are mounted in the plates 86 at each side of the spool. Adjacent one end, the spindles 85 are reduced in diameter to form a circumferential groove therein, as best shown at 87 in Figs. 10 and 12, and a retaining hook 88,

which is pivotally mounted on one of the plates, as shown at 89, engages the slot formed by the reduced portion 87 of the spool spindle. A flat spring 90 (see Fig. 10) engages the bottom of the hook 88 and holds it in engagement with the spindle. To remove a spindle or spool it is merely necessary to swing the hook 88 about its pivotal connection in a counterclockwise direction, as viewed in Fig. 10, which will compress the spring 90 and allow the spindle and spool to be removed.

In order to provide a variable braking effect on the spools I provide a pair of brake blocks 91, one on each side of the spool, and which bear against the spool flanges 92, as best shown in Figs. 10 and 12. The brake blocks 91 are pivotally mounted in a pair of trunnions 93 which, in turn, are mounted in the arms 94 and 95. These arms are also pivotally mounted on axes 96 so that the brake blocks may swing towards and away from the spool flanges as well as oscillate on the trunnions 93. Pivoted secured by the pin 97 to the ends of each of the arms 94 and 95 on one side of the spool is an element 98 having a piston-like head 99 (see Fig. 11) which is slidably mounted in the cylindrical shell 100. Pivoted secured by a pin 101 to the other set of arms 94 and 95 carrying the brake block on the other side of the spool, and at the ends thereof remote from the associated brake block, is a similar element 102 having an internally threaded stem 103 which projects into the shell 100. An adjusting nut 104 having a piston-like head adapted to slide in the shell 100 cooperates with the threaded stem 103. Within the shell 100 and compressed between the piston-like portion 99 of element 98 and the piston-like head of the nut 104 is a helical spring 105. From the foregoing it will be apparent that the action of the spring 105 tends to force the brake blocks 91 against the flanges 92 of the spool and that the pressure of the brake blocks against the spool flanges may be adjusted by turning the nut 104 to vary the compression on spring 105. In order to facilitate this, an opening 105' (see Fig. 12) is provided in the shell 100 through which a pin may be inserted to engage the circumferential holes in the nut 104.

Connected at one end to the bottom of each of the pins 97 and 101 are separate tension springs 106. The other ends of the springs 106 are connected together by a link 107 having a depending portion 108 which is pivotally connected to the end of the lever 109 by means of the pin 110; the lever, in turn, being pivotally connected by a pin 111 to the support 112. The lever 109 extends underneat the spool 14 and is provided at its free end, somewhat beyond the spool, with a cross member 113 which bears on the strand 17 or 19 as the case may be.

From the foregoing it will be apparent that, as illustrated in Figs. 10, 11 and 12, the spool is substantially full and the strands being drawn therefrom is comparatively remote from the axis of the spindle on which the spool is mounted. As the quantity of wire or other material on the spool is drawn therefrom, the strand gradually approaches the axis of the spool and thus by its co-action with the cross member 113 raises the front end of the lever 109 about its pivotal connection 111 and lowers the rear end of the lever 109, thereby increasing the tension on the springs 106. As the tension of the springs 106 increases the pressure of the brake blocks against the spool flanges due to the compression spring 105 decreases and, by adjusting the

compression of the spring 105 substantially any uniform tension within reasonable limits may be maintained on the strands.

It will also be apparent that, with the possible exception of portions of the tubes 27 which, as they oscillate, move radially towards and away from the axis of rotation, all of the moving parts of my machine revolve about the axis at fixed distances therefrom; and, although portions of the tubes 27 do move towards and away from the axis, these tubes are symmetrically disposed about the axis and the radial movement thereof of a tube on one side of the axis is balanced by the radial movement of the diametrically opposite tube. Therefore, the machine is perfectly balanced at all times.

It will also be clear that, since either the inner gates alone or the outer gates alone function to form a stable support for the spools 14 and also anchor said spools to the carrier 11, the outer gates might remain open at all times except when the inner gates are open. Thus, instead of opening and closing the outer gates both before and after the inner gates operate, the cams could be arranged merely to close the outer gates as the inner gates open and, thereafter, to open the outer gates and allow them to remain open until after the next strand passes through the first gate and the inner gates open.

Referring now to Figs. 26-32, inclusive, in which is illustrated my preferred means for supporting the spools on the inner table 11 so that the strands 19 from the spools on the outer table can pass thereunder, 205 represents a bearing block which is secured to the inner table 11 under each spool in any suitable manner. Rotatably mounted in the blocks 205 and in equidistantly spaced relation to each other, are three shafts 206 which extend in a direction generally radial of the machine, as shown in dotted outline in Fig. 28, but which are downwardly inclined, as best shown in Fig. 27. Secured to, or integral with each of these shafts, are two, elongated pinions or partial pinions 207 (see Fig. 32). Also secured to each of these shafts is a crank 208 having a cam follower 209 thereon which rides in a cam slot 210 and serves to oscillate the shafts 206 in sequence in the manner described below. Slidably mounted in each of the bearing blocks 205, are cylindrical bars 211 each of which has rack teeth 212 thereon cooperating with the teeth on the pinions 207. These bars are arranged in pairs with the bars of each pair diverging upwardly from each other at a substantial angle. One of the bars of each pair cooperates with one of the pinions 207, and the other bar cooperates with the other pinion on the same shaft. Thus it will be apparent that, when the shafts 206 are oscillated, the bars 211 will be reciprocated longitudinally thereof in the blocks 205. These bars serve to support the spools 213 on the inner table.

Each of the spool supports comprises a base 214 having openings into which the upper ends of the bars 211 project and which serve to hold said bases 214 above and in spaced relation to the blocks 205 so that clearance is provided between each base 214 and each block 205 for the passage of the strands 19 therethrough. If desired, a rubber cushioning sheet 231 may be interposed between the base 214 and the bearings in which the spool shaft is supported (see Fig. 29).

The shape of the cam slot is not shown but it is so simple that it seems unnecessary. There is simply a rise and fall in the cam slot for each spool on the inner table which moves the follow-

ers up and down and thus oscillates the shafts 206 in counter-clockwise sequence, as viewed in Figs. 26 and 28. Thus, referring to Fig. 28, the shaft 206 at the bottom of the figure, is first quickly oscillated so that the bars 211 associated therewith, are pulled quickly down into the block 205 and returned to their normal position so that there is a clear space between the base 214 of the spool carrier and said block 205 for the passage of the strand 19 until it approaches the bars on that shaft 206 which is in the middle of the figure. This middle shaft is then oscillated quickly to allow the wire to pass, and the shaft 206, at the top of the figure, is thereafter oscillated quickly to let the strand 19 pass out from under the base 214. These movements of the bars are, of course, in timed relation to the passage of the strands 19 under the spool carriers on the inner table.

From the foregoing, it will be apparent that only very slight movements of the bars 211 are necessary to pass the strands 19. Just as soon as the strand has passed each pair of the bars they are quickly pushed upwardly into the base 214 before the next set of bars 211 are pulled downwardly. Thus, the spool supports are always held in position on the inner table.

In order to maintain a uniform tension on the strands 17 which run from the spools 213 to the braiding point, the following mechanism is provided, reference being had particularly to Figs. 28-31, inclusive. A brake shoe 215 which bears against the wire on spool 213 is mounted on shaft 216 which is rotatably mounted in a fixed bearing 217 having a sloping cam face 218 (see Fig. 28), and an arm 219, which is connected to the brake shoe carrying means, is provided with a ball or roller 220 which bears against the inclined cam face 218 of the bearing 217.

Loosely mounted on the shaft 216 is a fiber or leather washer 221, a gear 222 and a helical spring 223 which is compressed between the gear 222 and a thumb screw 224 threaded on shaft 216. The brake shoe 215 which bears against the wire on the spool at all times is yieldingly held in contact therewith by means of the tension spring 225 (see Fig. 30). The gear 222 meshes with a gear 226 mounted on the spool shaft and which is connected to the flange of the spool by means of the pin 227 (see Fig. 29). Thus, as the spool 213 is turned by the wire drawn therefrom, the gear 226 turns with the spool and, in turn, rotates gear 222 which exerts a braking action on the spool due to the pressure of spring 223 which forces the gear 222 against washer 221.

As the quantity of wire on the spool diminishes, the ball or roller 220 moves down the inclined cam face 218 of the bearing 217 thus reducing the compression on spring 223 which reduces the braking pressure on gear 222 and spool 213. Thus, as the quantity of wire on the spool diminishes, and the distance between the axis of the spool and the point of tangency of the strand 17 with the cylinder of wire on the spool diminishes, the reduced braking effect compensates for the reduction in the turning moment exerted on the spool by the strand 17 and maintains the tension thereon substantially constant.

In order that the wire may be withdrawn from the spool at all times in a direction substantially at right angles to the axis of the spool, I provide a curved pulley guide 228 on which grooved pulley 229 is freely mounted. The strand 17 runs from the spool around the pulley 229 and thence to another grooved pulley 230 which is mounted on the base of the spool car-

rier and from which it runs to the braiding point. The pulley 229 moves back and forth along guide 228.

From the foregoing, it will be apparent that a braiding machine having the spool carriers and holders of the type shown in Figs. 26-31, inclusive, on the inner table, may be run at comparatively high speed and practically noiselessly because of the very slight movements of the bars 211 which are required to clear the passage for the strands 19 from the spools on the outer table.

In order positively to maintain the strands 19 from the outer spool out of contact with the spools 213 on the inner table when said strands are passing over the inner spools, as shown at 19' in Fig. 27, a guiding disk 232 for the strands 19 is mounted to rotate freely on the elevated end of the spool shaft.

While I have neither illustrated nor described the conventional capstan which draws the braided material upwardly from the braiding zone, because it is no part of my invention, it is to be understood that such a capstan, or equivalent means is employed and is driven through means (not shown) by the chain 200, the sprocket 201 on shaft 6', and the sprocket 202 on shaft 203 (see Fig. 2).

While I have described my invention in its preferred embodiment, it is to be understood that the words which I have used are words of description rather than of limitation and that changes within the purview of the appended claims may be made without departing from the true scope and spirit of my invention.

What I claim is:

1. In a braiding machine, the combination with a rotatable table, of a plurality of spools circumferentially-spaced about the axis of rotation of said table and adapted to carry strands to be braided, supports for said spools on said table each comprising two pairs of circumferentially-spaced gates with each pair thereof providing a stable support for the spool associated therewith independently of the other pair, means for rotating said table, means cooperating with each pair of gates when said table is rotating for opening said pair of gates when the other pair is closed and so constructed and arranged as to provide at timed intervals a passageway through said gates under the spools supported thereon, and means for guiding a plurality of strands alternately over and under a predetermined number of said spools to a braiding zone for braiding with the strands from said spools.

2. In a braiding machine of the character described comprising inner and outer rotatable tables each carrying a plurality of circumferentially-spaced spools adapted to carry strands of wire to be braided together at a braiding point above and substantially coaxial with said tables, and including means for rotating said tables in opposite directions, and means for guiding the strands from the spools on said outer table to said braiding point through zones both above and below the spools on said inner table; means supporting and securing each of the spools on said inner table to said inner table and comprising a base having a plurality of circumferentially-spaced openings therein; bars obliquely disposed to said base slidably fitted in said openings and supporting said base on and in vertically spaced relation to said inner table to allow strands from the spools on the outer table to pass therebetween; means cooperating with said bars for

reciprocating them out of and into said openings to provide clearance between said base and said table for the passage of the last mentioned strands; and means cooperating with said bars reciprocating means for actuating the same in sequence in timed relation to the passages of said strands from the spools on said outer table under the spools on said inner table.

3. The structure set forth in claim 2 in which said bars are provided with rack teeth thereon and said reciprocating means comprise gears having teeth cooperating with said rack teeth.

4. In a braiding machine of the character described comprising inner and outer rotatable tables each carrying a plurality of circumferentially-spaced spools adapted to carry strands of wire to be braided together at a braiding point above and substantially coaxial with said tables, and including means for rotating said tables in opposite directions, and means for guiding the strands from the spools on said outer table to said braiding point through zones both above and below the spools on said inner table; means for securing each of the spools on said inner table to said inner table and comprising a base having a plurality of openings therein disposed in circumferentially-spaced pairs with the openings of each pair radially-spaced from each other; pairs of bars each obliquely disposed to said base slidably fitted in said pairs of openings and supporting said base above and in spaced relation to said inner table; separate means cooperating with each of said pairs of bars for reciprocating them in and out of said openings to provide clearance between said base and said table for the passage of strands from the spools on said outer table therebetween; and means cooperating with each of said reciprocating means for actuating the same to reciprocate the pairs of bars associated therewith in circumferential sequence in timed relation to the passage of said strands from the spools on said outer table under the spools on said inner table.

5. The structure set forth in claim 4 in which said bars are provided with rack teeth thereon and said reciprocating means comprise gears having teeth cooperating with said rack teeth.

6. In a braiding machine of the character described comprising inner and outer rotatable tables each carrying a plurality of circumferentially-spaced spools adapted to carry strands of wire to be braided together at a braiding point above and substantially coaxial with said tables, and including means for rotating said tables in opposite directions, and means for guiding the strands from the spools on said outer table to said braiding point through zones both above and below the spools on said inner table; means for securing each of the spools on said inner table to said inner table and comprising a base having a plurality of openings therein disposed in circumferentially-spaced pairs with the openings of each pair radially-spaced from each other; a plurality of bars, disposed in circumferentially-spaced pairs with the bars in each pair diverging upwardly at a substantial angle to each other and at oblique angles to said base, slidably fitted in said pairs of openings and supporting said base above and in spaced relation to said inner table; a rack on each of said bars, pinions cooperating with the racks on each of said pairs of bars; and separate means for oscillating each pair of pinions independently of the other pairs to withdraw said pairs of bars out of the openings in said base and thereafter

to reinsert them in said openings in circumferential sequence and in timed relation to the passage of the strands from the spools on said outer table under the bases of the spool securing means on said inner table.

7. The structure set forth in claim 2 in which the axes of the spools on the inner table are disposed in planes approximately radially disposed to the axis of rotation of said table, and said machine is provided with means adapted to cooperate with the strands as they are drawn off said spools on the inner table for initially maintaining said strands substantially at right angles to said spools and thereafter guiding said strands directly to the braiding point.

8. The structure set forth in claim 4 in which the axes of the spools on the inner table are disposed in planes approximately radially disposed to the axis of rotation of said table, and said machine is provided with means adapted to cooperate with the strands as they are drawn off said spools on the inner table for initially maintaining said strands substantially at right angles to said spools and thereafter guiding said strands directly to the braiding point.

9. The structure set forth in claim 6 in which the axes of the spools on the inner table are disposed in planes approximately radially disposed to the axis of rotation of said table, and said machine is provided with means adapted to cooperate with the strands as they are drawn off said spools on the inner table for initially maintaining said strands substantially at right angles to said spools and thereafter guiding said strands directly to the braiding point.

10. In a braiding machine, the combination with a first spool carrier having a plurality of spool supports thereon; of circumferentially-spaced, separately movable means cooperating with each support for securing it in vertically spaced relation to said carrier, each of said separately movable means, independently of the other, positively securing the support with which it cooperates to said carrier; a second spool carrier also having a plurality of spools supported thereon each adapted to carry a strand to be braided; means for guiding each of said last mentioned strands to a braiding zone, means for effecting relative rotating movements of said spool carriers, means for moving said guiding means between positions where they will guide said strands to said braiding zone through zones above and below the strands from the spools on said first carrier, and means for moving said spool support securing means on said first carrier to provide open spaces between said supports and said first carrier for the passage of strands from said second carrier when in zones below the strands from said first carrier.

11. In a braiding machine, the combination with a first rotatably mounted spool carrier having thereon a plurality of supports for spools adapted to carry strands to be braided, said supports being circumferentially-spaced in fixed, radially-disposed relation to the axis of rotation of said carrier; of a second spool carrier rotatably mounted coaxially with said first carrier and having mounted thereon a plurality of supports for spools adapted to carry strands to be braided with said first mentioned strands; circumferentially-spaced strand guides mounted on said second carrier for guiding the strands from the spools on said second carrier to a braiding zone and disposed in outwardly, radially-spaced relation to the spools on said first carrier; means for

rotating said carriers in opposite directions about their common axis; means for oscillating said guides and the strands carried thereby between positions above and positions below the strands carried by the spools on said first carrier; a plurality of circumferentially-spaced, separately movable elements cooperating with each of the spool supports on said first carrier and securing said supports to said carrier in vertically-spaced relation thereto; and means for moving said elements in sequence and in advance of the strands moving with said second carrier when said strands are below the strands moving with said first carrier to provide free passages for the strands moving with said second carrier beneath the spool supports on said first carrier.

12. In a braiding machine the combination with a first and a second, coaxially-disposed, spool-carrying means adapted to carry spools having strands thereon to be braided together in a braiding zone above said means and adjacent the common axis thereof; of means for rotating said spool-carrying means in opposite directions about said axis; the strands from the spools on the first of said carrying means running directly therefrom to said braiding point; means on said second, spool-carrying means disposed in radially-outwardly-spaced relation to the spools on said first carrying means for guiding the strands from the spools on said second, spool-carrying means to said braiding zone; means for moving said last mentioned strands both over and under the strands from the spools on said first carrying means; circumferentially-spaced, movable gates below and on which the spools on said first carrying means are secured to said carrying means in vertically-spaced relation thereto; and means cooperating with said gates in timed relation with the movements of said strand guiding means for opening said gates in circumferential sequence to provide a free passageway therethrough for said guided strands below the strands running from the spools on said first carrying means.

13. In a braiding machine of the character described having an inner rotatable table provided with a plurality of circumferentially-spaced, strand supplying means thereon from which the strands run to a braiding zone; means for supporting and securing said strand-supplying means to said inner table in vertically-spaced relation thereto and comprising a plurality of circumferentially-spaced gates disposed between said table and each of said strand-supplying means, pivotal mountings for said gates about the axes of which said gates may open and close, means for rotating said table, and means actuated by the rotation thereof for opening and closing said gates in circumferential sequence to provide clear passageways between said strand-supplying means and said table for strands running from other strand-supplying means to said braiding zone to be braided with said first mentioned strands.

14. In a braiding machine, the combination with a first spool carrier having a plurality of circumferentially-spaced supports thereon adapted to carry spools bearing strands to be braided; of a second spool carrier having a plurality of circumferentially-spaced supports thereon adapted to carry spools bearing strands to be braided with the strands from the spools on said first carrier; means for rotating said carriers in opposite directions; means for guiding the strands from the second carrier to a braiding point through zones both above and below the supports on said first

carrier; means for securing each of the spool supports on said first carrier in vertically-spaced relation thereto and comprising a base having a plurality of circumferentially-spaced openings therein, a plurality of circumferentially-spaced bars slidably mounted in said first carrier, obliquely disposed to said base, slidably fitted in the openings in said base, and constituting the sole means for securing said base to said carrier in vertically-spaced relation thereto; and means for reciprocating said bars out of and into the openings in said base in circumferential sequence in timed relation to the passage of said strands from the spools on said second carrier under the spool supports on said first carrier to provide clear passageways thereunder for said strands and, at the same time maintaining said supports on said first carrier secured thereto.

15. The structure set forth in claim 13, in which said gates are provided with means lock-

ing said strand-supplying means to said table when in closed position.

RICHARD MAROOG.
